CLAIM

The ornamental design for an electronic atomizing device, as shown and described.

DESCRIPTION

FIG. 1 is a front, top perspective view of an electronic atomizing device, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of detail “9” identified in FIG. 2. The broken lines consisting of evenly spaced dash lines in the drawings depict portions of the electronic atomizing device that form no part of the claimed design. The broken lines consisting of long-short-long lines encircling the enlarged detail in FIGS. 2 and 9 are for annotative purposes only and form no part of the claimed design.
